CHANNEL CUTTER ATTACHMENT

John Ferrara, Rochester, N. Y.

Application January 5, 1938, Serial No. 183,508

6 Claims. (Cl. 112—45)

This invention relates to channel cutter attachments for shoe repair stitching machines and has for its object to provide a novel form of cutting mechanism for such an attachment in order that both straight and curved channels may be efficiently cut thereby.

This and other objects and attendant advantages will become more readily apparent from the detailed description of the invention which follows, reference being had to the accompanying drawing in which:

Figure 1 is a perspective view of the novel channel cutter attachment.

Figure 2 is a perspective view of a modified form thereof.

The channel cutter attachment forming the subject matter of my present invention is adapted for use with a stitching mechanism such as is illustrated in connection with the Resoling stitching machine illustrated in my prior Patent No. 1,924,737, issued August 29, 1933. The channel cutting mechanism of this prior patent is operated by a certain reciprocating member of the stitching mechanism. My present invention, while also operating in conjunction with the stitching mechanism, is driven independently thereof so that any rotating member thereof or a separate motor may be utilized for the purpose of furnishing the driving means therefor.

As illustrated in Figure 1 of the drawing, the channel cutting mechanism is embodied in and cooperates with the presser foot 1 which is located at the outer end of the bracket 2. In the bracket are provided the elongated holes 3 and 4 and the clamping screws 5 and 6 pass thru these holes to clamp the bracket to the arm 7 of the stitching machine. The holes are elongated so as to provide for a horizontal endwise adjustment of the bracket 2 on the arm 7. Mounted in the bracket 2 so as to be adjustable vertically thereon is the bearing block 8. This block is shaped so as to be guided in a straight line motion in the bracket. Mounted to rotate in the bracket but held against endwise movement by the pin 9 is the adjusting screw 10. This screw is threaded into the top of the bearing block 8 so that rotation thereof causes the bearing block to move up or down in the bracket.

Mounted to angularly slide in the bearing block 50 is the cutting knife or chisel 11. This chisel projects from the bearing block so that on the rapid reciprocation thereof the channel 12 is cut into the surface of a sole 13 that is fed under the presser foot during the stitching operation. The cutting knife or chisel is attached to the holder

14 and the latter is provided with the vertical cam slot 15. A crank pin 16, carried by the crank 17, projects into the slot 15 so that the rotation of the crank causes a rapid reciprocation of the knife holder and knife. The crank is carried by the shaft 18 and the latter is journaled in an extension 19 of the bracket 2.

The shaft 18 carries the pulley 20 and a belt 21 driven by a suitable rotating member of the stitching machine or an electric motor is adapted to rotate the shaft and operate the channel cutting mechanism.

As in the resoling stitching machine, above referred to, the stitching of the sole to the welt is adapted to take place in the channel cut by the cutting knife so that the stitching is embedded therein and will not be worn off by the wearer of the shoe.

In Figure 2 I have illustrated a modified form of the channel cutting mechanism. In this modification the channel cutter 23 is carried by an oscillating shaft 24 and projects laterally therefrom. The oscillating shaft is mounted in the bearing block 25 and a crank 26, operated by a link 27, is adapted to impart the proper oscillating motion from suitable driving means.

In oscillating, the cutter 23 cuts laterally into the sole and in doing so forms a channel 28 similar to that produced by the reciprocating cutter illustrated in Figure 1.

I claim:

1. An attachment for stitching machines comprising a bracket, a presser foot provided on said bracket, fastening means providing a horizontal adjustment for said bracket on the stitching machine, a bearing in said bracket, a channel cutter angularly mounted in said bearing and means carried by said bracket for rapidly reciprocating said cutter in said bearing.

2. An attachment for stitching machines comprising a bracket, a presser foot provided on said bracket, a bearing block carried by said bracket, a cutter angularly slidable in said bearing block and means carried by said bracket for reciprocating said cutter in said bearing block.

3. An attachment as set forth in claim 2 in which said bearing block is vertically movable with said cutter in said bracket relative to said presser foot.

4. An attachment for stitching machines comprising a bracket, a presser foot provided on said bracket, a bearing block carried by said bracket, a cutter mounted to reciprocate in said bearing block, means carried by said bracket and operatively engaging said cutter to cause said cutter

to rapidly reciprocate, and means for vertically adjusting said cutter with the cutter operatively connected with said first named means.

5. An attachment for stitching machines comprising a bracket, a presser foot carried by said bracket, a cutter mounted to reciprocate in said bracket, rotary operating means carried by said bracket, and means connecting said rotary operating means with said cutter and transforming 5
10 its rotary motion into a reciprocating motion for said cutter.

6. An attachment for stitching machines comprising a bracket, a presser foot carried by said bracket, a cutter mounted to reciprocate in said bracket, means for adjusting said cutter relative to said presser foot, rotary operating means, 5 and means connecting said rotary operating means with said cutter and transforming its rotary motion into a reciprocating motion for said cutter.

JOHN FERRARA. 10
